[57] CLAIM

The ornamental design for a folding pocket saw handle, as shown and described.

DESCRIPTION

FIG. 1 is a perspective view of a folding pocket saw handle showing my new design, it being understood that the broken line showing of a blade is for illustrative purposes only and forms no part of the claimed design; FIG. 2 is a top plan view thereof;

FIG. 3 is a front elevational view thereof;

FIG. 4 is a rear elevational view thereof;

FIG. 5 is a side elevational view thereof;

FIG. 6 is an elevational view of the side opposite from that illustrated in FIG. 5;

FIG. 7 is a bottom plan view thereof; and

FIG. 8 is a side elevational view thereof, with the blade in folded condition.
